In Great Britain June 8, 1950

Term of patent 14 years

(Cl. D26—14)

To all whom it may concern:

Be it known that I, John Charles Sydney Branson, a British subject, residing at 58 Croftdown Road, Harborne, Birmingham 17, in the county of Warwick, England, have invented a new, original, and ornamental Design for a Telephone Rest, of which the following is a specification, reference being had to the accompanying drawing, forming part thereof, in which:

Figure 1 is a front perspective view of a telephone rest showing my new design.

Figure 2 is a perspective view showing the rear and one side.

Figure 3 is a view in side elevation.

The telephone shown in dotted lines in Fig. 3 is for illustrative purposes only.

I claim:

The ornamental design for a telephone rest, as shown and described.

JOHN CHARLES SYDNEY BRANSON.
